(57) **CLAIM**

The ornamental design for a collage photo frame, as shown and described.

DESCRIPTION

FIG. 1 is a perspective view of a collage photo frame showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

A hinged photo collage having six rectangular photo frames positioned on an ornate support structure. As shown in FIGS. 1-7, the collage photo frame is shown in a flat configuration. However, it will be understood that the design encompasses the depicted collage photo frame when angled at the hinges.
